UNITED STATES PATENT OFFICE.

HUGH B. HOUSTON, OF PHILADELPHIA, PENNSYLVANIA, ASSIGNOR TO J. E. CALDWELL & CO.

DESIGN FOR A SPOON.

SPECIFICATION forming part of Design No. 21,715, dated July 19, 1892.

Application filed June 9, 1892. Serial No. 436,156. Term of patent 14 years.

To all whom it may concern:

Be it known that I, HUGH B. HOUSTON, a citizen of the United States, residing in the city and county of Philadelphia, State of Pennsylvania, have invented and produced a new and original Design for a Spoon, of which the following is a specification, reference being had to the accompanying drawing, forming part thereof.

10 The leading feature of my design for a spoon is a shank and tip of the form of a bunch of fiber, such as is placed on the distaff of a spinning-wheel.

15 In the accompanying drawing, to which reference is made, A designates the bowl of a spoon, and B the shank, and C the tip, thereof. The shank and tip are of the form of a

bunch of fiber—such as flax—as placed on a distaff of a spinning-wheel, the head of the bunch being flattened and having thereon a 20 representation D of a woman in the act of spinning and thirteen stars E. A ribbon F forms a knot on the head of the bunch. The lower end of the fiber is represented as separated and gracefully formed into letters suggestive of the initials of the society.

I claim—

The design for a spoon, substantially as shown and described.

II. B. HOUSTON.
